S. B. HESS.
ELECTRIC DISTRIBUTION SYSTEM.
APPLICATION FILED JULY 30, 1917.

Patented Apr. 1, 1919.

INVENTOR

Simon B. Hess

UNITED STATES PATENT OFFICE.

SIMON B. HESS, OF NEW YORK, N. Y.

ELECTRIC DISTRIBUTION SYSTEM.

1,298,711.

Specification of Letters Patent.

Patented Apr. 1, 1919.

Original application filed May 17, 1915, Serial No. 23,792. Divided and this application filed July 30, 1917, Serial No. 123,482.

To all whom it may concern:

Be it known that I, SIMON B. HESS, a citizen of the United States, residing at New York city, in the county of Queens and State 5 of New York, have invented certain new and useful Improvements in Electric Distribution Systems, of which the following is a specification.

This invention relates to certain novel 10 means whereby public service or other electric mains may be utilized as the source of supply for protective or other work circuits, thus eliminating the cost and annoyance incident to the use of batteries.

15 The method of obtaining a difference of potential by connecting work circuit leads to intermediate points on a resistance, the terminals of which are connected to the service mains, is well known in the art.

20 The object of this invention is to provide means for interrupting the supply to the work circuits whenever there is a disturbance in the condition of the work circuits.

A particular work circuit arrangement 25 with which this invention may be utilized is described and claimed in my copending application, filed May 17, 1915, Serial No. 28,792, of which application this application is a division.

30 Referring now to the drawings:—Figure 1 is a diagrammatic view showing a method of connecting the work circuits to the public service mains; Fig. 2 shows another method of connecting thereto.

35 In Fig. 1, S indicates the service mains which are shown as of the standard three-wire type. From the main S two taps 43 and 44 are taken (44 from the neutral or grounded main and 43 from either outside 40 main), the tap 43 leading to a pair of circuits in shunt, one of said circuits including the resistance R, the relay coil C, the wire 45, to the tap wire 44; and the other including the resistance R', the contact stop 46

45 (normally engaging the armature 47), the armature 47, the relay coil C', the wire 48, the resistance 10, to the tap wire 44. The work circuits are connected to the resistance 10 at the contact clips 11, 12 and 13 thereon. 50 The relay coils C and C' are arranged to oppose one another, and are so nearly balanced that armature 47 remains normally in its retracted position.

As an example of desirable values for dif- 55 ferent parts of the system let it be assumed

that:—the constant potential impressed upon the tap wires 43 and 44 is 120 volts; resistance R is 5000 ohms, resistance R' is 1000 ohms, resistance of coil C is 160 ohms, resistance of coil C' is 225 ohms, resistance 10 is 60 3000 ohms, and that the contact clips 11, 12, and 13 are so adjusted upon resistance 10 that the portion thereof between wire 48 and contact clip 11 is 1000 ohms, between contact clip 11 and contact clip 12 is 750 ohms, 65 between contact clip 12 and contact clip 13 is 750 ohms, and between contact clip 13 and tap wire 44 is 500 ohms; coil C has 2600 turns and coil C' has 1700 turns; 18 ampere turns are required to operatively affect 70 armature 47 to cause it to move away from stop 46.

Then the normal current flow through coil C is .0232 amperes, and the ampere turns are 60. If both work circuits are disconnected 75 from resistance 10 the current flow through coil C' is .0284 amperes and the ampere turns are 47. In this case there are 13 ampere turns acting upon the armature 47, which is not moved.

If both work circuits are short-circuited at resistance 10 the current flow through coil C' is .0440 amperes and the ampere turns are 73. In this case also there are 13 ampere turns acting upon the armature 47, which is 85 not moved. Hence, whatever work circuit resistance is connected to contact clips 11, 12, and 13, the current flow through coil C' can vary only between the extreme values (.0284 amperes and .0440 amperes) above 90 given, and the unbalanced ampere turns are insufficient to move armature 47.

If the work circuit has an assumed resistance of 125 ohms in each path and becomes grounded at contact clip 13, that portion of resistance 10 between contact clip 13 and tap wire 44 is short-circuited, and the current flow through coil C' is .0492 amperes and the ampere turns are 82. In this case there are 22 ampere turns acting upon the armature 100 47, which is operatively affected thereby and moved to attracted position, thus opening the circuit including the resistance 10. As soon as this circuit is opened, all of the 60 ampere turns of coil C become effective and 105 armature 47 is firmly retained in attracted position. It will be evident to one skilled in the art that a ground connection at any other point on either work circuit will cause a still greater flow of current through coil C' and 110

hence an even larger number of unbalanced ampere turns will affect armature 47.

It will now be seen that the work circuits are not disconnected from the public service mains in the event of a cross or a break, but are disconnected in the event of a ground, which might cause arcing at the point of contact.

10 The foregoing resistances, etc., are assumed only for purposes of illustration and may be varied at will to adapt this system for use with work circuits of different resistance, or requiring different voltage for their successful operation.

15 In Fig. 2 is shown an arrangement similar to that in Fig. 1, but with the insertion of an extra pair of contacts 49, 50 in the wire 44; 51 being a contact plate mounted on the armature 47, and 49 and 50 being stop contacts intended to coöperate therewith. This arrangement has the effect that a ground upon either work circuit will initiate the movement of armature 47, but upon the opening of the circuit through wire 44 at contacts 49 and 50, vibration of the armature takes place and consequently any lamps connected to that portion of the work circuits not shunted by the ground will be caused to flicker.

20 30 It will obviously be evident to one skilled in the art that various changes may be made in the arrangement of the wiring, resistances, and switches without departing from the spirit of the invention.

35 I claim:—

1. In an electric system, the combination with electric mains one of which is grounded, of a resistance connected between the grounded main and one of the other mains, 40 work circuits connected to intermediate points on said resistance, and means for automatically disconnecting said mains when said work circuits are grounded.

2. In an electric system, the combination 45 with electric mains, of a resistance connected between two of said mains, work circuits connected to said resistance, and a differential relay having one winding connected in series with said resistance and the other 50 winding connected in parallel with said resistance, said relay being arranged when operated to open the circuit through said resistance.

3. In an electric system, the combination 55 with electric mains, of a resistance connected

between two of said mains, work circuits connected to said resistance, and a differential relay having one winding connected in series with said resistance and the other winding connected in parallel with said resistance, said relay being arranged when operated to open the circuit through the winding in series with said resistance. 60

4. In an electric system, the combination with electric mains, of a resistance connected 65 between two of said mains, work circuits connected to said resistance, a differential relay having one winding connected in series with said resistance and the other winding connected in parallel with said resistance, a switch in series with one of said windings, and another switch in series with both of said windings, said relay being arranged when operated to open both of said switches. 70

5. In an electric system, the combination 75 with electric mains, of a resistance connected between two of said mains, work circuits connected to said resistance, and a differential relay having one winding connected in series with said resistance and the other 80 winding connected in parallel with said resistance, said relay being arranged when operated to open the circuit through one of said windings.

6. In an electric system, the combination 85 with electric mains, of a resistance connected between two of said mains, a work circuit connected to said resistance, and a magnet having one winding connected in series with said resistance, said magnet being arranged 90 when operated to open the circuit through said resistance.

7. In an electric system, the combination 95 with electric mains, of a resistance connected between two of said mains, a work circuit connected to said resistance, and a magnet having one winding connected in series with said resistance, said magnet being arranged when operated to open the circuit through said winding.

8. In an electric system, the combination with electric mains one of which is grounded, of a resistance connected between the grounded main and one of the other mains, 100 work circuits connected to intermediate points on said resistance, and means for automatically disconnecting said mains when either work circuit is grounded.

SIMON B. HESS.
